DESIGN FOR A COMBINED CHARGING AND TESTING APPARATUS AND STOCK STAND

Joseph C. Thomas, Akron, Ohio, assignor to Wing-
foot Corporation, Wilmington, Del., a corpora-
tion of Delaware

Application November 9, 1935, Serial No. 59,460

Term of patent 7 years

To all whom it may concern:

Be it known that I, Joseph C. Thomas, a citizen of the United States, residing at 338 Castle Boulevard, in the county of Summit and State of Ohio, have invented a new, original, and ornamental Design for a Combined Charging and Testing Apparatus and Stock Stand, of which the following is a specification, reference being had to the accompanying drawings, forming part thereof, showing my design, in which

Figure 1 is a perspective view of a combined charging and testing apparatus and stock stand, having the doors in open position, and

Figure 2 is a perspective view thereof having the doors in closed position.

I claim:

The ornamental design for a combined charging and testing apparatus and stock stand, as shown.

JOSEPH C. THOMAS.
